United States Patent Office

Des. 175,506

Patented Sept. 6, 1955

175,506

SEWING MACHINE HEAD

Clarence Karstadt, Santa Barbara, Calif., assignor to
Birtman Electric Company, a corporation of Illinois

Application November 19, 1952, Serial No. 22,369

Term of patent 14 years

(Cl. D70—1)

Des. 175,506

PAGE 2

Fig. 2.

Figure 1 is a side elevation of a sewing machine head showing my new design.

Figure 2 is a plan view of said head.

Figure 3 is an end elevation of said head.

Figure 4 is an end elevation thereof showing the opposite end of the head.

I claim:

The ornamental design for a sewing machine head, as shown.
